(57) **CLAIM**

The ornamental design for a toolbox, as shown and described.

DESCRIPTION

Cross reference is made to copending U.S. design patent application Ser. No. 29/653,387 entitled "Toolbox" by Christen et al., which was filed on even date herewith.

FIG. 1 is a perspective view of a toolbox showing our new design;

FIG. 2 is a front elevational view of the toolbox of FIG. 1; FIG. 3 is a rear elevational view of the toolbox of FIG. 1; FIG. 4 is a right side elevational view of the toolbox of FIG. 1;

FIG. 5 is a left side elevational view of the toolbox of FIG. 1;

FIG. 6 is a top plan view of the toolbox of FIG. 1; and, FIG. 7 is a bottom plan view of the toolbox of FIG. 1.

The broken lines shown in the drawings illustrate portions of the toolbox that form no part of the claimed design.
